UNITED STATES PATENT OFFICE.

LOYD I. ALDRICH, OF PEORIA, ILLINOIS, ASSIGNOR TO PREFERRED OIL BURNERS, INC., OF PEORIA, ILLINOIS, A CORPORATION OF ILLINOIS.

SAFETY CONTROL MECHANISM FOR FUEL ATOMIZERS.

Application filed July 5, 1924. Serial No. 724,542.

My invention relates to liquid fuel atomizing devices and more particularly to a safety control means therefor.

The object of my invention is in the provision of a thermal safety control mechanism operating upon an initial failure of ignition of the atomizing device to prevent the flow of fuel to the combustion chamber.

Another object of my invention is in the provision of a thermal safety mechanism included in the secondary circuit and adapted upon a failure of ignition to cut off the fuel supply to the combustion chamber.

Still another object of my invention is in the provision of a thermal safety member included in the electrical circuit of the fuel atomizing device and controlled by the action of the stack thermostat whereby a failure of operation of said thermostat will control the operation of the safety member to cut off the fuel supply to the combustion chamber.

Referring to the drawings I have shown in

Fig. 1, a diagrammatic view of a conventional fuel atomizing device and my particular control mechanism.

Fig. 2 is a side elevation of the thermal safety member, and

Fig. 3 is a view taken on the line 3—3 of Fig. 2.

Referring to the drawings, I have disclosed a conventional fuel atomizing device at "X", said device to be propelled by an electrical motor "Y", this being the conventional power mechanism for the so called domestic fuel burner. Inasmuch as the present application is directed not to a fuel atomizing device but to a control mechanism, therefor, I have not thought it necessary to go into a detailed description of the fuel atomizing device, other than to say that a fuel pump 10 and an air pump 11 provide means for mechanically atomizing the fuel and furnishing the required fuel mixture at the discharge point 12. A blower 13 provides added draft through the tube 14 and emission of same through the discharge nozzle 12.

The above description has been given merely to afford a complete understanding of my particular control system in its relation to a fuel atomizing device and it may be understood that any type of well known domestic fuel burner might well be used.

Applicant is aware of the fact that systems of control for domestic oil burners are well known in the art and the present application is directed mainly to a specific thermal safety device for preventing the flow of fuel to a combustion chamber upon initial or subsequent failure of ignition.

At 15 is shown a conventional thermostat adapted to be located in any portion of a dwelling that is desired to be heated, said thermostat controlling the operation of the atomizing device "X" or rather the electric motor "Y" propelling the same.

As is customary in such devices a relay switch 16 is located between the house thermostat and the fuel atomizer, said relay switch in this instance being shown as a mercury tube relay, portions making up same being as follows:

A bracket 17 suitably supported has connected thereto opposed magnetic coils 18 and 19, said coils being referred to commonly as on coils and off coils respectively. An armature plate 20 has an edge resting in V-bearings of the bracket 17 so as to oscillate between the coils 18 and 19, and carries mercury contact tubes 21 and 22 at the opposite ends respectively thereof which by the oscillation of the armature plate 20 are tilted so that the mercury therein is shifted to make and break the circuits through said tubes.

The above relay switch has its magnetic coils in the secondary circuit of the transformer 23, the magnetic coils being energized in said circuit to move the contact lever 20 in either direction, this direction being controlled by the formal thermostat 15 located in the dwelling, and at a distance, therefrom. In the normal operation of the device a lowering of the house temperature throws the house thermostat to an on position, thereby magnetizing the on coils 18, and attracting the contact member 20, and tipping the mercury bulb 21 to a position to energize the electric motor "Y" through the 110 volt circuit from the street.

Obviously the heating of the dwelling to such a degree as to throw the thermostat to the off position would result in the magnetizing of the off coils and hence the cutting out of the fuel burner.

My invention relates to a safety mechanism controlling the operation of the device in case of an exceptional circumstance

namely when there would be a failure of ignition of the discharged fuel and a consequent accumulation of unignited dangerous fuel.

5 I accomplish the above result by inserting a thermal safety control member in the secondary circuit but adapted to control a switch in the 110 volt circuit as well.

10 My safety control mechanism is also associated with my ignition mechanism which operates as follows:

15 A formal gas inlet is shown at 24 and a pipe 25 leads to a point adjacent the discharge nozzle of the burner. A valve 26 is located therein, said valve having its stem 27 controlled by a magnetic coil 28, said coil being located in the secondary circuit or rather the circuit from the transformer. Similarly a spark coil is shown at 29, said 20 spark coil controlling the operation of formal electrodes 30 disposed also adjacent the discharge end of the gas tube and the fuel discharge nozzle. The spark and gas are energized inasmuch as they are in the 25 secondary circuit by the movement of the house thermostat or rather the relay and operate simultaneously with the fuel atomizing device, under normal conditions igniting the discharged fuel mixture therefrom.

30 A formal thermostat 31 made up of two metals having a different co-efficient of expansion is located in any position to be controlled by the temperatures in the combustion chamber, said thermostat usually being 35 located in the stack. The operation of the stack thermostat makes or brakes an electrical contact by movement of a mercury bulb 32 disposed in operable position with relation to the thermal elements therein.

40 As said before, the spark and gas mechanisms are energized by the movement of the thermostat and normally ignite the discharge fuel mixture, however, some means must be thrown into operation to control the 45 time of operation of these ignition mechanisms and this time element is the formal thermostat above described. In other words, if there is an ignition of the fuel mixture, there will be consequently a raising of 50 the temperature in the combustion chamber and hence a movement of the stack thermostat. Under the above described condition, such movement of the thermostat will break the electrical circuit of the spark and gas 55 valves thereby cutting out the spark mechanism and permitting a closing movement of the gas valve by de-energizing the magnet 28.

60 My thermal safety mechanism is intimately associated with this ignition mechanism and is made up of the following portions. A thermal or bi-metallic strip 33 is suitably supported at 34 in a longitudinal position. A resistance coil 35 surrounds said member, 65 said coil being in the secondary circuit and

connected by the wire 36 to the transformer. The connection of this resistance coil 35 to the transformer is such, due to the ground 37, that an electrical circuit will also be maintained therein either during the operation or non-operation of the fuel atomizing device, with the result that normally a considerable heat will be developed in said resistance coil and hence a corresponding movement of the thermal member which it surrounds. The secondary circuit normally induces such heat through this coil 35 as to move the thermal member 33 to a downward position and upon a lessening of the current to such resistance coil, there would be naturally a decrease of heat and a consequent rise of said thermal member. The projecting or operating end 38 of this thermal member has operative engagement with a switch member shown in detail in Figs. 2 and 3. This safety switch member is suitably supported by means of brackets 39, and is made up of the following portions. An insulated block 40 is pivoted in the brackets 39 and has a manually operable lever 41 connected thereto. A pair of separate contacts 42 are supported by brackets 43, there being a separate contact point 44 upon the insulated block 40 for each contact 42. A 45 downwardly projecting portion 45 on the insulated block has a protruding lug 46 thereon, said lug projecting through an aperture 47 in one of the brackets 39. This lug is adapted to engage a catch portion 49 upon a lever 50 pivoted at 51 on the above mentioned bracket 39. Now this lever 50 is controlled by the movement of the thermal member 33 inasmuch as the projecting end 38 thereof underlies one end of said lever as shown in Fig. 3.

50 Obviously when the thermal member is suitably heated and depressed thereby, the end 52 of the lever resting thereon will drop down to a position wherein the latched portion 49 will engage the pin 46. This safety latching movement is accomplished by manual movement of the lever 41.

55 When the current to the coil 35 is diminished there is a decrease of temperature which serves to straighten out the thermostatic element 33 and raise the outer or free end thereof, thus elevating the end 52 of the lever 50 and releasing the latch 49 from engagement with the pin 46. Upon release of this latch the insulating block 40 drops by gravity and breaks the connection between the contacts 42 and 44.

60 One pair of contacts 42-44 controls the circuit to the motor "Y" of the fuel atomizing device while the other pair of contacts 42-44 are in the secondary circuit from the transformer that operates the magnetic relay.

65 The operative relation of my described thermal member in the secondary circuit

may perhaps be more clearly understood if it be said that normally the circuit controlling said thermal member will heat the member 33 to such an extent that it will 5 maintain a depressed position. However, upon the use of current in the secondary circuit to energize the spark coil as well as the gas coil the capacity of the transformer will be strained with the result that a less amount 10 of current can at this time be used by the resistance coil 35 and hence a decrease in the heating thereof occurs.

I may connect the operation of my described thermal safety member with the operation of the ignition mechanism of the fuel burning device now, by saying that said thermal member is maintained in a lower-most position practically at all times due to the constant heat maintained by the current 20 passing through the coil 35. The thermal safety switch is at this time latched so as to hold the contacts 42 and 44 in a closed position. Now upon the energizing of the fuel burning device due to the movement of 25 the thermostat, and consequently the relay, with a simultaneous energizing of the spark and gas coil, due to the movement of the relay, a decrease in the temperature of the coil 35 will take place at the same time as 30 above described, due to the straining of the capacity of the transformer. An immediate movement of the thermal member 33 will not take place but a very gradual movement will however begin. As above described, if 35 there is a normal movement of the stack thermostat due to a rise in temperature in the combustion chamber there will be a consequent cutting out of the spark and gas coils. This cutting out of said coils will 40 naturally permit the full capacity of the transformer being directed to the coil 35 with a resultant rise in temperature and the movement of the thermal member again to its first or normal position.

45 Of course, it is understood that the move-

ment of the thermal member is timed to such an extent that no tripping of the safety switch is possible until such thermal member has reached a considerably elevated position.

In case of failure of initial ignition there 50 will be no movement translated to the stack thermostat and hence the spark and gas coils will use a considerable portion of the transformer capacity with the result that eventually the decrease in heating of the coil 35 55 will result in a sufficiently elevated movement of the thermal member to trip the lever 50, hence releasing the latch portions and throwing the safety switch thereby cutting out not only the high voltage circuit including the fuel atomizing device but also the branch of the secondary circuit that includes 60 the relay, spark coil, gas coil, etc.

In view of the explanation of the operation of the device in connection with the 65 specific description thereof, no further explanation of the operation of the device is thought necessary, except to say that upon a cessation of combustion condition after initial ignition, there will be a second energizing of the spark and gas coils and if the discharging fuel is not ignited at this time, the safety device will operate as above described to cut out the fuel atomizer.

What I claim is:

In an apparatus of the class described, the combination of a burner, motor operated means for supplying a fuel mixture to the burner, a thermostat for controlling the operation of the motor operated means, a 80 transformer having a coil in the secondary circuit for heating said thermostat, and a burner igniting circuit shunted around said heating coil so that closing of the latter circuit diminishes the current in the heating coil of the thermostat and permits a slow motor stopping movement of said thermostat.

In testimony whereof I affix my signature.
LOYD I. ALDRICH.
